(57) CLAIM

The ornamental design for a car including toy-car, motor car, replica car and scale-model car, as shown and described.

DESCRIPTION

FIG. 1 is a top plan view of the design for a car including toy-car, motor car, replica car and scale-model car, showing my new design.

FIG. 2 is a bottom plan view thereof.

FIG. 3 is a left side elevational view thereof.

FIG. 4 is a right side elevational view thereof.

FIG. 5 is a front view thereof; and,

FIG. 6 is a rear view thereof.
